INDICIA BEARING DEVICES FOR VERTICALLY SLIDABLE DOORS

Glen G. Robbins, Larned, Kans.

Application December 21, 1953, Serial No. 399,232

8 Claims. (Cl. 40—125)

The invention is more particularly adapted to vertically slidable doors such as are employed for door openings of shops and garages.

Vertically slidable shop and garage doors are at times damaged by a truck or automobile or other vehicle prematurely attempting to pass through such door opening during the upward movement of the vertically slidable door.

One of the objects of my invention is to provide means tending to overcome and lessen such dangerous and damaging incidents; such means consisting of an indicia bearing sign in the form of a panel containing warning indicia thereon and supported on a rod that is releasably carried on stationary brackets fastened to the outer sides of the door jambs and adapted to be engaged by and carried upwardly upon a pair of laterally spaced brackets secured to the bottom end portion of the door in such position that, during the upward opening movement of the door into open position, the sign will hang suspended from its supporting rod carried on the door supported brackets preferably with at least a lower portion of the sign projecting below the bottom edge of the door.

Another object of the invention is to provide means of the above described character which may not only function as a visible warning signal and retardant to prevent vehicles prematurely entering a door way during the upward movement of the door, but, may also function as a sign carrying thereon advertising indicia in lieu of or in conjunction with warning indicia.

Another object of the invention is found in the provision of simple means for preventing unauthorized removal of the sign from its supports on the outer sides of the door jambs during such times when the door is closed.

Still another object of the invention resides in the provision of a device of the character described which shall be simple in construction, low in cost of manufacture, and very easily installed for use on presently employed vertically slidable doors without change or modification of the doors or their operating mechanisms.

The various features of novelty whereby the present invention is characterized will hereinafter be pointed out with particularity in the claims, but, for a full understanding of the invention and of its construction and advantages, reference may be had to the following detailed description taken in connection with the accompanying drawing, wherein:

Fig. 1 is a front elevation of a vertically slidable door showing a preferred embodiment of my invention applied thereto.

Fig. 2 is an enlarged view, with portions of the door jamb broken away to show details, showing in illustrative form an end elevation of my invention with the door in closed position.

Fig. 3 is an illustrative end elevation, with portions of the door jamb broken away, showing an operative position of my improved device after the upwardly moving door has lifted the warning sign from its supporting brack-

2

ets on the door jamb and engaged the sign with its sign-carrying brackets thereby suspending the sign below the bottom edge of the door during its upward movement into open position.

Fig. 4 is a cross-section taken on line 4—4 of Fig. 1. Fig. 5 is a cross-section taken on line 5—5 of Fig. 1. As shown on the drawing in its preferred embodiment, my invention is applied to a vertically slidable door designated generally by numeral 10. The door is operable between the side door jambs 11. The door includes the stiles 10^a and bottom rail 10^b and the jambs are provided with exterior finishing strips 11^a.

My invention includes the preferably elongated sign or indicia bearing panel designated by numeral 12 which may consist of a panel of metal, wood or fabric or any other suitable material and which, for illustrative purposes, is shown on the drawing as consisting of fabric such as, for example, a waterproof canvas 12^a.

The panel 12 of canvas is doubled over its self along the bottom edge portion, as at 12^b, to provide an elongated pocket for a weight-rod 12^c to keep the fabric panel taut. Along its upper edge the panel 12 is reinforced in any suitable manner as by a pair of metallic bars 12^d and 12^e provided with a pair of laterally spaced U-shaped metallic hangers 12^f embracing the panel-supporting rod 13 and riveted to the reinforcing bars 12^d and 12^e and the upper end of the fabric held between these bars. The upper portion of the panel is also secured to the reinforcing bars 12^d and 12^e in any suitable manner as, for example, by small spaced rivets 14. The rod 13 is preferably tightly held within the hangers 12^f as the panel 12 may freely swing about the ends of rod 13.

When the door 10 is in closed position, as shown in Fig. 1, the outer ends of the panel-supporting rod 13 are loosely carried on a pair of brackets 15 each of which consists of a bar having an intermediate portion 15^b bent relatively angularly to the end portions 15^a and 15^c thereof. Each bracket 15 is secured to the outer face of the door jamb strip 11^a as by screws 16 extending through the lower end portion 15^a; the brackets 15 being so mounted that their intermediate portions 15^b together with the outer faces of the jamb strips 11^a form V-shaped seats for the end portions of the panel-carrying rod 13 during the time the door 10 is in closed position as shown in Fig. 1.

I prefer to provide the brackets 15 with the upstanding upper end portions 15^c disposed in a vertical plane parallel to and offset relatively to the vertical plane of the lower portions 15^a and I may state that for all practical purposes the upper vertical portions 15^c could be omitted.

The stiles 10^a of the door are each provided with a lifter bracket 17 secured thereto near the bottom portion of the door. Each bracket 17 is substantially of deformed channel shape consisting of upstanding parallel flanges 17^a and 17^b offset horizontally and vertically relatively to each other and interconnected at their lower ends by a web portion 17^c that slopes downwardly from the flange 17^a so as to form a V-shaped seat 17^d.

Assuming the door 10 is closed and the panel 12 is suspended from its rod 13 on the brackets 15 as shown in Figs. 1 and 2, when the door 10 is moved upwardly toward open position the lifter brackets 17, being laterally offset relatively to the brackets 15, will engage the rod 13 by their downwardly sloping portions 17^c and will cause the rod 13 to slidably pass into the V-shaped seats 17^d to be carried therein with the sign suspended therefrom on the door and in such suspended position the sign 12 will hang below the bottom edge of the door and thus will clearly be visible to the driver of a vehicle approaching and about to enter the door opening and thereby warning such driver of the moving door accentuated by the sus-

pended warning sign and the clearly visible warning indicia thereon.

As a means for preventing thieves from stealing the sign 12 by simply lifting same from its supporting brackets 15 when the door is in closed position, I provide a pair of angle irons 18 which are so secured to the door stiles 10^a that their lateral legs 18^a extend just above the outer ends of rod 13 when the door is closed position, as shown in Fig. 1, and thereby prevent unauthorized removal of the sign from the supporting brackets 15.

To further resist unauthorized removal of the sign 12 from its supporting brackets 15 as by shifting the supporting rod 13 laterally along its longitudinal axis to thus evade the obstructions to its vertical lift imposed by the angle irons 18, I provide a pair of abutments 19 which are secured to the rod 13 and positioned near the angle irons 18, when the door is closed position. An attempt to laterally shift the rod 13 will be obstructed by the engagement of either one of the abutments 19 with one or the other of the legs 18^a of the angle irons 18.

In its downward movement from raised open position into closed position, the door 10 will carry the sign 12 on brackets 17 until the ends of rod 13 engage and seat themselves on the brackets 15 whereat the sign 12 will become suspended on rod 13 across the door opening and the door then will continue to descend into its closed position whereat the lateral legs 18^a of the angle irons 18 will become positioned just above the rod 13 thus together with the abutments 19 cooperating to obstruct upward or lateral movements of the sign-supporting rod 13 to thereby prevent unauthorized removal of the sign from its supporting brackets 15.

Obviously, my invention is operative without the door angle irons 18 and abutments 19 on the rod 13.

As shown in Fig. 1, the sign 12 is provided with warning indicia in the phrase "Danger-Stop." As stated above, the sign may carry thereon advertising indicia in lieu of or in conjunction with the warning indicia.

It is also obvious that my device is operative in a similar manner as above described when the sign 12 is installed on the rear or inner side of the door 10 as illustrated by the dot and dash lines in Fig. 4. In such operation the brackets 15 are mounted on the inside faces of the interior finishing strips 11^a of the door jambs for support thereon of the rod 13 with the sign 12 suspended therefrom on the rear or inner side of the door 10 when the door is in closed position. The lifter brackets 17 being installed, in such operation, on the inside faces of the interior door stiles 10^a and since the chances of unauthorized removal of the sign are remote the use of the angle irons 18 and abutments 19 may conveniently be dispensed with.

Various changes may be made in the details of the parts and members by those skilled in the art to which my invention apertains without departing from the spirit of my invention as defined in the appended claims, hence, I do not wish to be understood as limiting my invention to the details disclosed herein for purposes of illustration of the preferred embodiment of the invention.

I claim:

1. In a device of the kind described, the combination with a door adapted to slide vertically between a pair of laterally spaced vertically disposed jambs of the door opening into open position, of an indicia-bearing sign releasably supported on the jambs of the door opening when the door is in closed position, and means on said door adapted to engage and lift and carry said sign on said door during the upward movement of said door into open position.

2. In a device of the kind described, the combination with a door adapted to move vertically between a pair of

laterally spaced vertically disposed jambs of the door opening into open position, of an indicia-bearing sign releasably carried on stationary supports mounted on the jambs of the door opening above the bottom edge of the door, means mounted below said supports on and near the bottom edge of said door adapted to lift and carry said sign on said door in suspended position, during the upward movement of said door into open position, with at least a lower portion of said sign projecting below the bottom edge of said door.

5. In a device of the kind described, the combination with a door adapted to be moved vertically between a pair of laterally spaced vertically disposed jambs of the door opening into open position, of an indicia-bearing sign supported on a rod extending laterally across the door opening and releasably carried on stationary brackets, mounted on the jambs of the door opening, when the door is in closed position, additional brackets carried on said door close to the bottom edge thereof adapted to engage said rod and thereby lift and carry said sign on said door during its upward movement into open position.

15. In a device of the kind described, the combination with a door adapted to be moved vertically between a pair of laterally spaced vertically disposed jambs of the door opening into open position, of an indicia-bearing sign supported on a rod extending laterally across the door opening and releasably carried on stationary brackets, mounted on the jambs of the door opening, when the door is in closed position, additional brackets carried on said door close to the bottom edge thereof adapted to engage said rod and thereby lift and carry said sign on said door during its upward movement into open position.

20. In a device of the kind described and as set forth in claim 3 including means on said door preventing lifting of said rod and sign from their support on said stationary brackets during the time said door is in closed position.

25. In a device of the kind described and as set forth in claim 4 and including means on said rod preventing

30. shifting of said rod, in a direction parallel to its longitudinal axis, to thereby release said rod from its support on said stationary brackets during the time said door is in closed position.

35. In a device of the kind described, the combination with a door adapted to slide vertically between a pair of laterally spaced vertically disposed jambs of the door opening into open position, of an indicia-bearing sign supported on a pair of laterally spaced hangers mounted on a rod extending laterally across the door opening,

40. stationary brackets mounted on the jambs of the door opening in a horizontal plane adapted to releasably support the ends of said rod when said door is in closed position, a pair of additional brackets mounted on said door in vertical planes laterally offset from the vertical planes of said stationary brackets and below the horizontal plane of said stationary brackets, said additional brackets on said door functioning, during the upward movement of said door, to engage and lift and carry said rod and sign on said door in its upward movement into open position while at least a lower portion of said sign projects below the bottom edge of said door.

45. In a device of the kind described and as set forth in claim 6 including a pair of angle irons mounted on the door stiles having lateral legs extending above said rod when the door is in closed position thereby preventing lifting of said rod and sign from their support on said stationary brackets when said door is in closed position.

50. 7. In a device of the kind described and as set forth in claim 7 including a pair of laterally spaced abutments on said rod close to said angle irons disposed in vertical planes spaced inwardly of the vertical planes of said angle irons adapted for preventing the shifting of said rod in a direction parallel to its longitudinal axis to thereby release said rod from its support on said stationary brackets during the time said door is in closed position.
